Primary Examiner — Sandra Snapp*Assistant Examiner* — Altaira J Swangin(74) *Attorney, Agent, or Firm* — Dennemeyer & Associates, LLC; Steven M. Shape(57) **CLAIM**

The ornamental design for a monitor for automobile, as shown and described.

DESCRIPTION

FIG. 1 is a front perspective view of a monitor for automobile with the new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a rear perspective view thereof.
